Attorney.

UNITED STATES PATENT OFFICE.

ROY PAUL MILLER DAVIS, OF MOUNT UNION, PENNSYLVANIA.

SLICKER.

Application filed August 14, 1926. Serial No. 129,180.

My invention relates to slickers and more particularly to rotary slickers employed in slicking machine made brick.

In the manufacture of brick, after the charge of mud has been projected into or otherwise deposited within the brick mold, the surplus material is removed and the top of the brick slicked or smoothed by means of a rapidly rotating slicker which is either moved across and in contact with the top face of the mold while the mold is held stationary, or the mold may be moved beneath the slicker and the latter held stationary except for its rotary movement during this operation. In practicing either method considerable difficulty has been experienced due to the fact that the mold contacting surface, or what may be termed the bottom face of the slicker disks wear more rapidly at and adjacent to their periphery than at the center, thus necessitating frequent refinishing to present the required perfectly flat surface.

My invention has for its object to overcome the objectionable uneven wearing of the slickers by forming the slicker disk with a centrally disposed insert of softer material, or one having less wearing qualities than the surrounding or peripheral portion of the slicker disk.

In the accompanying drawings wherein I have illustrated a preferred embodiment of my invention:

Figure 1 is a top plan view of the slicker disk illustrating the manner of securing the insert; and

Figure 2 is a section on the line 2—2 of Figure 1.

Referring more particularly to the drawings 5 denotes a slicker disk preferably of steel or iron adapted to be connected to the usual slicker stem (not shown) by any suitable fasteners (also not shown) at the points 6. The bottom face of the disk is formed with a relatively deep circular recess 8 leaving a relatively thin top central portion or wall 9 and a relatively thick beveled peripheral portion 10, the latter having a relatively narrow wearing face 10'. The wall 9 is formed with dove-tail openings 11, preferably four in number and arranged at equal distances apart.

Inserted within the centrally disposed circular recess 8 and extending into the dove-tail openings 11, is an insert of softer consistency than the material from which the slicker disk is made. In practice I have found that inserts of babbitt or lead, when used with the steel or iron slicker disk have the desired wearing qualities and that a slicker so made wears uniformly, the mold 60 contacting surface of the slicker remaining flat until the slicker disk is completely worn out. However, disk shaped inserts of other material such as wood and the like have proven relatively satisfactory in an iron or steel disk, when centrally positioned substantially as shown in the drawings.

Where an insert of metal such as babbitt or lead is employed, the insert is preferably 70 poured.

Having thus described my invention, what I claim as my invention is:

1. A rotary slicker disk of hard material having a centrally disposed circular recess formed in its bottom face, and an insert of relatively soft material inserted in said recess.

2. A rotary slicker disk of hard material having a centrally disposed circular recess formed in its bottom face, said disk having 80 a peripheral slicking face or surface encircling said recess, and an insert of relatively soft material completely filling said recess and flush with said peripheral slicking face.

3. A rotary slicker disk of hard material having a centrally disposed circular recess formed in its bottom face, said disk having a peripheral slicking face or surface encircling said recess, and an insert of relatively soft material completely filling said recess and 90 flush with said peripheral slicking face, the diameter of said peripheral slicking face being considerably less than the diameter of said insert.

4. A rotary slicker disk having a peripheral slicking face of hard material and a centrally disposed disk shaped slicking face of relatively softer material.

In testimony whereof I affix my signature.

100.

ROY PAUL MILLER DAVIS.
